MOLDER'S TOOL

Fred Oliver Garrison, South Gate, Calif.

Application June 16, 1942, Serial No. 447,283

7 Claims. (Cl. 22—38)

This invention relates to improvements in molders' tools, and particularly to devices intended for use in cutting and reaming riser channels in the molded sand forms comprising the hollow receptacles commonly referred to in the foundry industry as molds or flasks, preparatory to pouring the molten metal.

Briefly described, the foundry operation of producing metal castings generally consists of making a sectional mold formed of specially prepared relatively soften earthen composition known as molder's sand, over a pattern made of wood, metal or other suitable material having a body of substantially the same shape as the casting to be produced, removing the pattern by separating the various sections of the finished mold, re-uniting the latter so as to result in a hollow inner chamber which is then in the exact form or shape of the metal body to be cast, and thereupon perforating the upper wall of the finished mold so as to form therein a plurality of suitably located vertically disposed channels having exterior orifices in communication with the hollow interior, one of which channels is intended for use as a mouth for receiving the pour of molten metal, while other oppositely disposed channels act as exit passages for air and gases, and for containing the excess of poured metal constituting the overflow known as risers. After completion of the mold and the final cleaning thereof, which is usually by means of compressed air, molten metal is poured into the form through one of the inlets previously described until the level of the metal has reached a satisfactory point within the riser channels, thereby completely filling in all areas within the interior chamber which forms the casting proper. Thereafter the cast is allowed to set, the sectional mold being later disassembled and the finished casting removed and cut to eliminate undesired portions of the metal studs or risers which project from the casting as a result of the filling of the riser channels.

As previously mentioned, the function of the riser channel is to allow escape of air and gases from the interior of the mold during the pour, so as to prevent the forming of air-bubbles or the like in the casting, and more particularly to receive a sufficient amount of the excess metal poured to create back-pressure upon the metal within the mold during the time the metal remains in a state of flux, so as to force the metal to all areas within the mold and maintain a fully expanded condition of the same, in order to prevent undue shrinkage and other deficiencies, flaws, or imperfections, however slight, which

might render the entire cast a failure, especially when precision work is involved, such as aluminum aircraft parts and other essential defense products.

A riser channel is usually cut by perforating the molded sand with the open end of a section of pipe or tubing, which results in a channel of substantially uniform diameter throughout its length; and in order to render this opening more efficient so as to enable it to contain a greater weight of molten metal for creating back-pressure, it has been common practice to taper its outer portion into substantially frusto-conical shape, usually by reaming with some form of available present-day hand tool such as a cement worker's trowel, a knife, a scoop, or the like, the use of which invariably results in a roughly-shaped, un-uniform opening at best even when the workman has acquired considerable technique in manipulating such a tool in executing the operation. But regardless of whether the work is done expertly or inexpertly, it always requires a considerable amount of time if performed in this fashion, and frequently results in damage to the mold when the operator is inexpert or careless, so that repair work is necessary before continuing with the regular process, causing much loss of time and thereby adding very materially to the cost of operations, especially when the mold becomes damaged beyond repair and a new mold must be made. When the molder happens to be working on a piece-work or similar basis it can readily be seen that such difficulties are apt to result in a serious loss to him personally. A factor of much greater importance at the present time, however, is the resulting delay in producing urgently needed war equipment.

Therefore the principal object of the present invention is the provision of a simply constructed, inexpensive device in the nature of a riser reamer by the use of which the cutting of tapering riser openings can be performed more speedily and accurately than heretofore with a minimum of effort, and whereby production of castings, particularly those used in national defense industries, can be greatly expedited and their cost materially reduced.

Another object of the invention is to provide a riser reamer for use by molders in foundries or the like, which device, when constructed of metal, will require a minimum amount of said material, thus effecting a considerable saving in steel or other metals over types of tools heretofore used for performing work of this character.

A further object of the invention is to provide an extremely useful and accurate molder's riser

reaming tool, which shall be simple of construction and long-wearing, composed of a minimum of easily replaceable parts, and which may be of such composition as to require a minimum amount of materials of the kind required for executing orders used in war and defense production, and the use of which tool will render the tasks of the operator more pleasant and at the same time enable him to produce more and better work with less effort than heretofore.

Other and further objects of the invention will be apparent from the disclosures in the accompanying drawing and following specification.

The invention, in a preferred form, is illustrated in the drawing and hereinafter more fully described.

In the drawing:

Figure 1 is a longitudinal elevation, partly in section illustrating the riser reamer of this invention.

Figure 2 is a top view of the same.

Figure 3 is a bottom view of the same.

As shown in the drawing:

The reference numeral 10 indicates an elongated stem provided at its upper end with an integral handle 11, the stem 10 preferably having a tapering lower end 12 the bottom of which may be suitably slotted or notched to form guides 13 for purposes hereinafter set forth.

Attached to the stem 10 at a suitable point intermediate its ends is a strong transverse web or plate 14 concentric with and of considerably larger maximum diameter than the stem. The element 14 may be made of metal or any other suitable material adapted for this purpose, and it can be shaped in any design which will permit of assembly of the parts as hereinafter set forth.

The plate 14 may be attached to the stem in immovable, fixed position by making same integral with the stem 10, but I prefer to provide it with a central aperture 15 and to equip the stem 10 with an exterior thread 16 over which the plate 14 may slide freely upon the stem, but of a sufficiently snug fit to prevent sidewise play, so that the plate may be movable longitudinally and adjustable by means of a pair of lock nuts 17, 18 adapted to threadably engage the stem and bear against contact washers 19, 20, which, in turn, are adapted to engage the upper and lower faces of the plate 14 when tightened so as to lock the plate rigidly in fixed position at a given level and render it non-rotatable upon the stem 10.

The stem 10 is adapted to carry a plurality of cutting or reaming elements or surfaces the working edges of which follow a straight line tapering from the periphery of the plate 14 in a central direction toward the lower end of the stem 10 so as to be capable of cutting or reaming out a frusto-conical area from a body of molder's sand or the like. Such reaming elements may be of any composition and shape suitable for this purpose, such as straight or spirally curved blades, fins, or the like, which could be mounted on the stem 10 in any well known manner.

However, I have found that a very inexpensive though highly satisfactory form of reaming element for this particular purpose, and one which tends to conserve materials by eliminating the necessity of the relatively wide bladed elements, can be made as best shown in Figs. 1 to 3, inclusive, by forming said reaming elements of a plurality of lengths of thin wire 21, the ends of which may be looped around the shanks of screws or bolts 22 mounted on the plate 14 adjacent the periphery thereof, and whereby such looped por-

tions may be securely fastened to said plate. I prefer to make the fastening elements 22 in the form of bolts slideable through suitable orifices cut through the body of the plate 14, and to thread such bolts so that they may be tightened by means of ordinary nuts 23. In order to save materials I also prefer to shape the plate 14 in the general form of a cross having a series of oppositely disposed radially directed transverse arms 24, each arm being provided at its outer end with a guide or notch 25. The middle portion of each wire 21 is strung through one of the guides 13 located at the working end of the stem 10 and led through the arm notches 25 to prevent slippage. Quite obviously the wires 21 could be made shorter so as merely to span the distance between the periphery of the plate 14 and the notched point 13 of the stem and fastened at the latter point by any conventional method. However, I have found in practice that the structure previously described is much to be preferred, inasmuch as a considerable saving of wire is effected, assembly and replacement time is reduced to a minimum, and the longer wire strung through the notches 13 in the manner shown automatically serves to equalize the tension of each wire on both sides of the stem. Thus the wires 21 may be stretched to any degree of tension desired while in process of mounting as above described and subsequently the wires may at all times be kept taut by forcing slight upward movement of the plate 14 upon the stem 10 by means of the elevating nut 18 and the upper lock nut 17, a fraction of a turn of the nut 18 after correspondingly loosening the lock nut 17 usually being sufficient to bring about the desired result. Both assembly and adjustment can be readily accomplished by even the most inexperienced person with no more equipment than a pair of common pliers. The elements 17, 18 may be wing nuts, if desired.

Replacement of the wires 21 themselves, when required, is simple and inexpensive due to the ready availability of the standard wire materials, and making the replacement involves little or no inconvenience or loss of time on the part of the user, who needs no special tools or equipment for making the replacement himself.

The cutting edges of any till made in accordance with this invention may be lengthened or shortened by conventional means regardless of the type of cutters employed, by merely mounting same in any manner that will allow for such change. For example, in the preferred modification shown herein this can be accomplished by moving the member 14 toward or away from the working end of the tool by means of the adjusting elements 17 and 18 after loosening the fastening elements 22 and either taking up on or releasing the wires 21, as the situation calls for, said wires being preferably made in an original length sufficient to meet maximum requirements within a given range, and capable of re-looping and tightening as hereinbefore described. Furthermore, a wide variety of equivalents well known in the art could be substituted for certain of the individual parts, and innumerable changes and substitutions would be possible throughout a wide range in executing the invention without departing from the basic principles thereof.

To illustrate only a few of the changes possible: The shank of the threaded stem could be provided with a longitudinal slot adapted to cooperate with key means integral with the plate 14 for preventing turning of the plate about the

stem, yet providing the same degree of adjustability as demonstrated in the preferred modification. Fastening of the wires 21 to the plate 14 might be by ordinary set screws adapted to be threadably introduced into corresponding tapped openings in the plate 14, or the wires could be simply attached by tying same directly to the plate. Holes could be drilled through the stem 10 in lieu of the notches 13. Or, if it is desired to separately fasten each length of wire at the working end of the stem 10, this would be possible by simply shaping the point of attachment in a manner that would permit of the fastening method desired, such as by providing prongs or hooks integral with the stem, or by using set screws, or the like. Also, if desired, the plate 14 may be in any form which will allow lateral adjustment of the cutting elements to wider or narrower diameter, so as to have the effect of changing the angle of the cutting elements for producing enlarged or restricted orifices of any desired depth.

In using the device to ream an opening, the molder simply grasps the tool by its handle 11 and inserts the tapering end 12 into the riser channel to be widened or reamed out. Then, by exerting slight pressure or by allowing the weight of the tool to provide the desired pressure and at the same time rotating the tool about its stem while its reaming elements are in contact with the sand surface to be cut out, the cutting elements 21 will ream out the soft earthen material about the channel opening, producing a smooth-surfaced, uniform, funnel-shaped orifice of the depth and taper desired, reducing the loosened sand to a finely granulated state which can be easily removed by the usual methods, as by air pressure, the entire operation being of but a few moments duration and eliminating entirely the hazard of gouging out sizable lumps of sand or accidentally damaging the mold through carelessness, accident, or otherwise, as would likely occur when crude or improper tools are used, since the present device is obviously capable of use only according to the method indicated and cannot fail to produce anything but uniformly satisfactory results.

The great amount of time saved by the molder by using this device is an extremely important contributing factor toward expediting production, which is now very vital on defense orders, and the ease with which the tool can be manipulated renders more pleasant the molder's task, which involves very tiresome manual labor. Since the molder's compensation is often measured by the number of perfect molds produced by him in a given period of time, my device, which is no more expensive than unsatisfactory tools, will enable him to earn more money with less effort than heretofore, as the acceptable quality of his work will never vary as to the operation described. Accordingly, a uniformly excellent standard of quality will be maintained in castings produced, and waste, expense, and loss of time due to rejections are reduced to a minimum.

While the foregoing remarks have described the use of the invention only in the art of producing metal castings, its use is by no means limited to this particular field. I have merely chosen the metal foundry as an illustration. Obviously my tool would be usable in numerous other industries where similar problems may arise or similar production methods are used.

I claim as my invention:

1. A tool for cutting tapering riser openings in

foundry molds, comprising in combination, an elongated body in the general form of a stem having a handle end and a working end, said working end comprising a cutting head surrounding said stem and concentric therewith and attached thereto so as to be incapable of independent rotation about said stem while the tool is in use, said cutting head tapering at an angle from a uniform radius extending laterally about and in spaced relation to said stem, toward a remote focal point disposed in the general direction of and concentric with the working end of the stem, said cutting head presenting a plurality of diagonal, spaced, adjustable reaming elements.

2. A tool for cutting tapering riser openings in foundry molds, comprising in combination, an elongated body in the general form of a stem having a handle end and a working end, said working end comprising a cutting head surrounding said stem and attached thereto so as to be immovable and nonrotatable about said stem while the tool is in use, said cutting head comprising a pair of oppositely disposed cutting edges tapering at an angle from a uniform radius extending laterally about and in spaced relation to said stem, toward a remote focal point disposed in the general direction of and concentric with the working end of the stem, said cutting head being adjustable in length.

3. A tool for cutting tapering riser openings in foundry molds, comprising in combination, an elongated body in the general form of a stem having a handle end and a working end and an intermediate body portion, said working end comprising a cutting head surrounding said stem and concentric therewith and attached to said intermediate body portion so as to be incapable of independent rotation about said stem while the tool is in use, said cutting head tapering at an angle from a uniform radius extending laterally about and in spaced relation to said intermediate body portion, toward a remote focal point disposed in the general direction of and concentric with the working end of the stem, said cutting head including a plurality of longitudinally disposed tightly stretched lengths of wire.

4. A tool for cutting tapering riser openings in foundry molds, comprising in combination, an elongated body in the general form of a stem having a handle end and a working end and an intermediate body portion, said working end comprising a cutting head surrounding said stem and concentric therewith and attached to said intermediate body portion so as to be incapable of independent rotation about said stem while the tool is in use, said cutting head tapering at an angle from a uniform radius extending laterally about and in spaced relation to said intermediate body portion, toward a remote focal point disposed in the general direction of and concentric with the working end of the stem, said cutting head including a plurality of longitudinally disposed tightly stretched lengths of wire, and means on the tool permitting concentric adjustment of the angular area defined by said cutting head.

5. A tool for cutting tapering riser openings in foundry molds, comprising in combination, an elongated body in the general form of a stem having a handle end and a working end and an intermediate body portion, and having a threaded section on said intermediate portion, an enlarged radial plate co-axial with the stem and provided with a central aperture and mounted on said stem so as to allow slidable, snug-fitting longitudinal

adjustment thereof upon the stem, internally threaded nut means mounted upon the threaded section of the stem for locking the plate immovably and nonrotatably in adjusted position in relation to the stem while the tool is in use, and a plurality of longitudinally disposed reaming elements comprising wires spaced in radial symmetry and held in fixed position about said stem and fastened to and strung between fixed radial points adjacent the periphery of the plate and said working end so as to taper at an angle from a uniform radius extending laterally about and in spaced relation to said intermediate body portion, toward a remote focal point disposed in the general direction of and concentric with the working end of the stem.

6. A tool for cutting tapering riser openings in foundry molds, comprising in combination, an elongated body in the general form of a stem having a handle end and a working end and an intermediate body portion, and having a threaded section on said intermediate body portion, an enlarged radial plate co-axial with the stem and provided with a central aperture and mounted on said stem so as to allow slideable, snug-fitting longitudinal adjustment thereof upon the stem, internally threaded nut means mounted upon the threaded section of the stem for locking the plate immovably and nonrotatably in adjusted position in relation to the stem while the tool is in use,

a plurality of longitudinally disposed reaming elements comprising wires spaced in radial symmetry and held in fixed position about said stem and fastened to and strung between fixed radial points adjacent the periphery of the plate and said working end so as to taper at an angle from a uniform radius extending laterally about and in spaced relation to said intermediate body portion, toward a remote focal point disposed in the general direction of and concentric with the working end of the stem, and means on the tool permitting concentric adjustment of the angular area defined by said reaming face.

5 7. A tool for cutting tapering riser openings in foundry molds, comprising in combination, an elongated body having a handle end and a working end, and a reaming head formed about said working end and concentric therewith and attached thereto so as to be incapable of independent rotation about said working end while the tool is in use, said reaming head tapering at an angle from a uniform radius extending laterally about and in spaced relation to said working end, toward a remote focal point spaced away from said working end and in line with the longitudinal axis of said body, said reaming head presenting a plurality of diagonal, spaced, adjustable reaming elements.

FRED OLIVER GARRISON.
